LOUDSPEAKER

Maurice W. Widener, San Jose, Calif., assignor to Ampex Corporation, Redwood City, Calif., a corporation of California

Filed Mar. 1, 1961, Ser. No. 92,435

10 Claims. (Cl. 179—115.5)

This invention relates to loudspeakers, and particularly to loudspeakers having diaphragms movable by electro-magnetic means engaging the peripheries thereof.

In the noted art it has been recognized that a diaphragm moved by means engaging the periphery thereof can give improved performance if a very large part of the diaphragm is unyieldingly rigid so as to displace the air more uniformly to create the sound waves desired. The larger is the rigid area of the diaphragm, the greater is the volume of air displaced on each vibrational stroke, and the greater is the average amplitude of displacement. Also, each such diaphragm is limited in range by an upper resonant frequency at which the rigidity of the element is overcome and at which it begins to undulate or flex uncontrollably so as to produce undesirable distortions in the sound produced. Thus, the more rigid the diaphragm, the wider is the frequency range across which the speaker can be used without resonance. In effect, it is desired to make the diaphragm more like the solid head of a piston and less like the flexible head of a drum.

Previously, attempts to design a speaker embodying such a diaphragm have been limited by the circumstance that high audible frequencies require a low-mass diaphragm because very quick alternating response and reversal of movement of the diaphragm is needed to produce these frequencies. Assuming a given material of high strength and low unit mass (e.g., aluminum), it is nevertheless true that the lower the total mass, the thinner the diaphragm must be, and the less rigid.

Until now, no speaker is known that can reproduce the higher audible frequencies without being limited in range on the lower side at approximately 3000-4000 cycles per second.

Accordingly, it is an object of this invention to provide a loudspeaker having a non-resonant frequency range encompassing substantially all of the desirable audible frequencies above approximately 500 cycles per second.

It is another object of the invention to provide a loudspeaker having a response flatness range of novel extent and of improved constancy.

It is still another object of the invention to provide a loudspeaker of improved performance and capable of being manufactured in simple and inexpensive form for economical sale and use.

A loudspeaker in accordance with the present invention satisfies the foregoing and other purposes by making use of a diaphragm in the shape of an oblate dome having increased resistance to distortion under forces acting in an axial direction of the dome, and maximum rigidity in proportion to mass; and this diaphragm is acoustically coupled to a sound box the cavity of which is tuned to a lower resonant frequency than the free resonant frequency of the mass of the moving parts and the suspension thereof.

Other objects and advantages will be explained in the following specification, considered together with the accompanying drawing, in which:

FIGURE 1 is a cross-sectional perspective elevation view of a loudspeaker constructed in accordance with the invention;

FIGURE 2 is a fragmentary broken-away plan view, to an enlarged scale, taken substantially on the plane of line 2—2 of FIGURE 1;

2

FIGURE 3 is an enlarged view of that portion of FIGURE 1 enclosed within the arcuate line 3—3 thereof.

FIGURE 4 is a schematic view illustrating the shape of a dome constructed in accordance with the invention.

Referring now to FIGURE 1 there is shown a lower housing 11 defining a cylindrical cavity 12 and having a bottom wall 13 reinforced by flanges 14, the wall 13 being provided with a small vent opening 16. In the upper portion of the housing 11 there is seated and firmly affixed an upper housing 17 provided with an inwardly directed flange 18 at the lower end thereof, the flange defining a central opening 19. On the flange is affixed a toroidal permanent magnet 21 formed, for example, of "Alnica," and having a frusto-conical outer surface 22. The housing 17 is part of one of the pole pieces of the magnet 21 and is preferably formed of soft iron. The central opening 23 of the magnet is in registry with the opening 19 of flange 18. Surmounting the magnet 21 is a soft iron pole piece 24, having a toroidal shape and defining an opening 25 registering with the opening 23 of the magnet. On top of the housing 17 and in the same plane with pole piece 24 is affixed a toroidal cover plate 27, which is also part of the pole piece represented by the housing 17 and is also made of soft iron. The plate 27 defines a central opening 28, so that the cover plate circumferentially encompassing the pole piece 24 is spaced therefrom to define the opening 28 as a space between the cover plate and pole piece. A ring 29 of electrically insulating material is affixed to the upper portion of the cover plate 27 to form a portion of the upper wall of the acoustical cavity through which electrical leads are to be passed, as described below. A diaphragm mounting ring 30 is affixed to the upper portion of the ring 29 and mounts a resilient collar 31, which has a wavy cross-sectional shape to permit motion. The collar 31 in turn serves as a mounting for a thin aluminum diaphragm 32 in the shape of an oblate dome oriented with the concave side inward and communicating with the central openings of the pole pieces 24 and magnet 21. Also affixed to the collar 31 is a downwardly extending cylinder 33 formed, for example, of stiff paper on which is mounted an electrical coil 34. The cylinder 33 is extended to dispose the coil 34 (best seen in FIGURE 3) within the space 28 between the cover plate 27 and the pole piece 24. A plug 36 made of acoustical damping material such as phenolic bonded fiberglass is mounted in the central portion of the magnet opening 23 so as to define within the interior of the apparatus the lower cavity 12 and an upper cavity 37. A damping element 38, made of solid non-magnetic material, is centrally mounted as by means of a spider 39 on the pole piece 24 and projecting upwardly in the upper cavity to a position in which the upper surface 41 of the element is spaced closely beneath the peak portion of the dome shaped diaphragm 32, the surface 41 being formed to substantially the same conformation as the confronting peak portion of the diaphragm. A pair of electrical leads 42 and 43 are arranged projecting through the insulating ring 29 to be coupled with the coil 34, as hereinafter described.

It is here noted that the cavities 12 and 37 are completely sealed to form what would be, in the absence of the vent opening 16, an air-tight chamber. Under some conditions of use or during shipping as by aircraft, there would be danger of the loudspeaker blowing up. The opening 16 is provided to circumvent such happenings.

The structure described above is further illustrated in FIGURE 2, together with a protective cover 48 of rigid, acoustically transparent net material in the shape of a dome and affixed to the outer portion of ring 30 to cover the diaphragm 32.

Referring now to FIGURE 3, there is shown the electrical lead 42 extending through the insulating ring 29 and electrically coupled to a flexible strip 51 of electrical conducting material having undulations, one end of which is extended to pass through a hole 52 in the paper cylinder 33 and is electrically coupled to an extending end 53 of the conductor forming the coil 34.

Referring now to FIGURE 4, one method for establishing the cross-sectional shape of the diaphragm 32 is illustrated. The shape is that of an exponential curve, and particularly a symmetrical curve 61 having an axis 62 of symmetry. To construct one-half of the curve, a circular arc 63 is struck from the axis 62 and from a center 64 on the axis 62. The arc 63 has a predetermined angle defined by a radius 65, the angle in this example being five degrees. From a second center 67, lying on the radius 65 and spaced from center 64 for a distance equal to one-tenth the length of radius 65, a second arc 68 is laid off from arc 63. The arc 68 is also of five degrees and is defined by an outer radius 69. A third arc 71 also of five degrees and of radius 72 equal to 0.9 of radius 69 is then laid off. The process is continued until the tangent 74 to the curve 61 at the outermost portion thereof lies at an angle of approximately sixty degrees to a line 76 that is perpendicular to the axis 62; that is to say until the tangent 74 lies at an angle of approximately thirty degrees to the axis 62. It will be seen that each pair of adjacent arcs have a common tangent at the juncture of the arcs, and form a smooth curve.

In this figure, the arc 81 of a circle centered on axis 62 and passing through the peak point 82 and the outermost point 83 of the curve 61, is shown for comparison. It will be noted that the curve 61 has a much sharper degree of curvature (i.e., shorter radius of curvature) in the vicinity of point 83 than has the arc 81; that is, the tangent 74 of the curve 61 at point 83 is substantially closer to being parallel with the axis 62 than would be the tangent to the arc 81 at point 83.

In operation, an electrical signal representing the wave fluctuations of sound is supplied to the electrical leads 42 and 43, and the varying current passing through the coil 34 causes the coil together with the cylinder 33 and dome 32 to be rapidly displaced upward and downward with respect to the magnet 21 and pole pieces 24. The wavy shape of the conductor 51 and of the collar 31 permits substantial extension of these elements in an axial direction of the apparatus so as to impose the least possible resistance to the displacement required at the greater amplitudes, and so as to prevent fatigue and wearing out of the two parts. The damping element 38 helps to reduce the amplitude of vibration of the diaphragm 41 at the highest frequencies of vibration so as to control the quality of sound emitted. In part, the element 38 effects damping as by serving as an anvil against which air displaced by the diaphragm 32 in downward movement is compressed, the space between the element 38 and the diaphragm being relatively restricted so as to hinder the escape of air toward the periphery of element 38. This effect is also operative during upward movement of the diaphragm 32, because the space available for radial inward rush of air is also relatively restricted. The presence of the plug 36 as a dividing portion between the upper and the lower acoustical cavities also helps to restrict the displacement of air between the cavities at the lower frequencies of vibration and so to improve the acoustical quality of the reproduced sound.

The cross-sectional shape of the diaphragm 32 has an important effect in increasing the stiffness and rigidity of the dome so that equivalent rigidity can be obtained with less mass of material, and conversely so that with a given mass of material a greater rigidity can be obtained, and the range of frequencies that can be reproduced is extended at the upper limit.

It will be understood that the condition of least rigidity for a diaphragm is that in which the diaphragm is flat; and that the condition of greatest rigidity would be that in which the diaphragm most closely approached being in the shape of a cylindrical wall, but a cylindrical wall would have no cross-sectional surface area suitable for displacing air in an axial direction. The provision of a spherical dome, as known in the art, is a partly successful compromise, but the oblate shape of the dome used in the present invention more closely approaches an ideal form. As illustrated in FIGURE 4, the oblate shape of the present dome provides a resolution of forces more nearly approaching parallelism with the axis of the diaphragm at the peripheral portions thereof, where the greatest strain is focused when the diaphragm is suddenly moved as by forces applied to its periphery. The mass of the dome, and the inertia of this mass, is more readily moved without distortion of the dome when the dome has a more sharply acute curvature with respect to the axis at the point where the moving forces are applied. On the other hand, at the portions of the dome near the axis where the curvature is flatter than it would be in a spherical section, the mass remaining radially inward of any selected circular section of the dome is comparatively quite small and the effect of the increased flatness is not deleterious. In short, the dome of the invention has a smaller radius of curvature in the portions thereof that lie at a greater radius from the axis and where greater rigidity is needed to withstand the inertia forces of the central or axial portion of the dome, and has greater flatness near the axial portion where the strength does not have to be so great to produce rigidity.

The range of non-resonant response of the diaphragm having been broadened by the construction above described, the loudspeaker is additionally tuned as by careful dimensioning and proportioning of the cavities 12 and 37 so that the lower resonant frequency of the coupled cavities is lower than the frequency of free resonance of the diaphragm and moving parts attached thereto, so that the speaker as a whole is limited in its response range only by the lower resonant frequency of the cavities and by the upper resonant frequency of the diaphragm.

In a preferred example of the device, constructed and proportioned substantially as illustrated in the drawing, a response flatness range of ± 1 decibel has been achieved between the frequencies of 500 cycles per second and 15,000 cycles per second.

If desired, as shown in FIGURE 5, and as an alternative to the use of damping element 38 for damping the resonance of the speaker, the lead 42 may be coupled to a damping circuit 44, comprising an inductor 45, a capacitor 46 and a resistor 47 connected in parallel, the circuit 44 being in series between the coil 34 and a constant-voltage amplifier (not shown).

Thus, there has been described in the foregoing a wide frequency range loudspeaker in which an acoustical chamber is coupled to a diaphragm in the shape of an oblate dome oriented with the concave side facing the chamber, so as to provide a very wide range of non-resonant frequency response.

What is claimed is:

1. A wide frequency range loudspeaker comprising: a housing defining an acoustical chamber closed at one end; a diaphragm mounted closing the other end of said chamber and arranged for axial movement relative to said housing to cause air pressure variations within and without said chamber, said diaphragm having a flexible peripheral portion secured to said housing and a rigid central portion in the shape of an oblate dome oriented with the concave side facing said chamber; and electromagnetic means engaging the periphery of said dome portion for effecting axial motion of said dome portion in response to variations of a control signal so as to produce corresponding sound waves.
2. A loudspeaker as defined in claim 1, wherein the

cross-sectional shape of said dome is defined by an exponential curve.

3. A wide frequency range loudspeaker comprising: a housing defining an acoustical chamber closed at one end; a diaphragm mounted closing the other end of said cavity and arranged for axial movement relative to said housing to cause air pressure variations within and without said chamber, said diaphragm having a flexible peripheral portion secured to said housing and a rigid central portion in the shape of an oblate dome oriented with the concave side facing said chamber, said dome having a cross-sectional shape characterized by a symmetrical curve having an axis of symmetry, each half of said curve having a plurality of adjacent arcuate portions extending from said axis outwardly, each pair of adjacent portions having a common tangent at the juncture thereof, the radius of each portion being a predetermined function of the radius of the adjacent axially inward portion, the angle of each portion being a predetermined function of the angle of the adjacent axially inward portion, and the tangent to the outermost part of the outermost portion being at an inclination of approximately thirty degrees to said axis of symmetry; and electromagnetic means engaging the periphery of said dome portion for effecting axial motion of said dome portion in response to variations of a control signal so as to produce corresponding sound waves.

4. A wide frequency range loudspeaker comprising: a housing defining an acoustical chamber closed at one end; a diaphragm mounted closing the other end of said cavity and arranged for axial movement relative to said housing to cause air pressure variations within and without said chamber, said diaphragm having a rigid central portion in the shape of an oblate dome oriented with the concave side facing said chamber, and a flexible peripheral portion of substantial radial width constituting a cantilever mounting for said dome, whereby said dome is axially movable for maximum excursion with minimum unit distortion of said peripheral portion; and electromagnetic means engaging the periphery of said dome portion for effecting axial motion of said dome portion in response to variations of a control signal so as to produce corresponding sound waves.

5. A wide frequency range loudspeaker comprising: a housing defining an acoustical chamber closed at one end; a diaphragm mounted closing the other end of said cavity and arranged for axial movement relative to said housing to cause air pressure variations within and without said chamber, said diaphragm having a flexible peripheral portion secured to said housing and a rigid central portion in the shape of an oblate dome oriented with the concave side facing said chamber; electromagnetic means engaging the periphery of said dome portion for effecting axial motion of said dome portion in response to variations of a control signal so as to produce corresponding sound waves; and said chamber being tuned to a resonant frequency lower than the free resonant frequency of said dome together with the moving parts attached thereto.

6. A wide frequency range loudspeaker comprising: a housing defining an acoustical chamber closed at one end; a diaphragm mounted closing the other end of said cavity and arranged for axial movement relative to said housing to cause air pressure variations within and without said chamber, said diaphragm having a flexible peripheral portion secured to said housing and a rigid central portion in the shape of an oblate dome oriented with the concave side facing said chamber; said chamber being tuned to a resonant frequency lower than that of said dome; electromagnetic means engaging the periphery of said dome portion for effecting axial motion of said dome portion in response to variations of a control signal so as to produce corresponding sound waves; and a quantity of acoustical damping material disposed in said chamber intermediate the ends thereof.

7. A wide frequency range loudspeaker comprising: a housing defining an acoustical chamber closed at one end; a diaphragm mounted closing the other end of said cavity and arranged for axial movement relative to said housing to cause air pressure variations within and without said chamber, said diaphragm having a flexible peripheral portion secured to said housing and a rigid central portion in the shape of an oblate dome oriented with the concave side facing said chamber; electromagnetic means engaging the periphery of said dome portion for effecting axial motion of said dome portion in response to variations of a control signal so as to produce corresponding sound waves; and a damping element mounted within said chamber, said element having a portion facing said dome and spaced therefrom so as to restrict the air flow immediately behind said dome when said dome is axially moved.

8. A wide frequency range loudspeaker comprising: a housing defining a chamber closed at one end; a toroidal magnet mounted co-axially within said housing and spaced from said closed end so as to define a first end compartment of said chamber communicating with the central opening of said toroidal magnet; a diaphragm covering the other end of said housing and spaced from said magnet so as to define a second end compartment of said chamber communicating with said central opening of said toroidal magnet, said diaphragm having a flexible peripheral portion secured to said housing and a rigid central portion in the shape of an oblate dome oriented with the concave side facing said chamber; an electrical coil co-axially affixed to the peripheral portion of said dome and extending toward said magnet; and means for supplying electrical current to said coil, whereby said coil is attracted to and repulsed from said magnet in response to variations in the strength and direction of said current, and whereby said dome is conjointly displaced to generate sound waves in the air within and without said chamber.

9. A wide frequency range loudspeaker comprising: a housing defining a chamber closed at one end; a toroidal magnet mounted co-axially within said housing and spaced from said closed end so as to define a first end compartment of said chamber communicating with the central opening of said toroidal magnet; a diaphragm covering the other end of said housing and spaced from said magnet so as to define a second end compartment of said chamber communicating with said central opening of said toroidal magnet, said diaphragm having a flexible peripheral portion secured to said housing, said peripheral portion being of substantial radial width and having a plurality of concentric folds for expansion of said peripheral portion in either axial direction, said diaphragm also having a rigid central portion in the shape of an oblate dome oriented with the concave side facing said chamber; an electrical coil co-axially affixed to the periphery of said dome and extending toward said magnet; and electrical leads for supplying electrical current to said coil, said leads being mounted to extend radially inward through said housing and being affixed at the ends thereof to the ends of said coil so as to form an electrical connection therewith, the portions of said leads extending between said housing and said coil being provided with a plurality of transverse folds for resilient extension of said leads upon axial movement of said coil; whereby said coil is attracted to and repulsed from said magnet in response to variations in the strength and direction of said current, and whereby said dome is conjointly displaced to generate sound waves in the air within and without said chamber.

10. A wide frequency range loudspeaker comprising: a housing defining a chamber closed at one end; a toroidal magnet mounted co-axially within said housing and spaced from said closed end so as to define a first end compartment of said chamber communicating with the central opening of said toroidal magnet; a diaphragm covering

the other end of said housing and spaced from said magnet so as to define a second end compartment of said chamber communicating with said central opening of said toroidal magnet, said diaphragm having a flexible peripheral portion secured to said housing, said peripheral portion being of substantial radial width and having a plurality of concentric folds for expansion of said peripheral portion in either axial direction, said diaphragm also having a rigid central portion in the shape of an oblate dome oriented with the concave side facing said chamber; an electrical coil co-axially affixed to the peripheral portion of said dome and extending toward said magnet; a pair of electrical leads for supplying electrical current to said coil, said leads being mounted to extend radially inward through said housing and being affixed at the ends to the ends of said coil so as to form an electrical connection therewith, the portions of said leads extending between said housing and said coil being provided with a plurality of transverse folds for resilient extension of said leads upon axial movement of said coil; a quantity of acoustical damping material mounted in the central opening of said toroidal magnet; and a damping element mounted within said second end compartment, said element being shaped to conform to the concave side of said dome and being

spaced therefrom so as to restrict the flow of air immediately behind said dome when said dome is axially moved, said element being mounted by means of a spider attached thereto and to the adjacent portions of said toroidal magnet, whereby said coil is attracted to and repulsed from said magnet in response to variations in the strength and direction of said current, and whereby said dome is conjointly displaced to generate sound waves in the air within and without said chamber.
